UNITED STATES PATENT OFFICE.

CHARLES M. STEVENSON, OF ROCKFORD, ILLINOIS.

STANCHION AND OPERATING MECHANISM THEREFOR.

1,286,441.

Specification of Letters Patent.

Patented Dec. 3, 1918.

Application filed August 3, 1917. Serial No. 184,253.

To all whom it may concern:

Be it known that I, CHARLES M. STEVENSON, a citizen of the United States, residing at Rockford, in the county of Winnebago and State of Illinois, have invented certain new and useful Improvements in Stanchions and Operating Mechanism Therefor, of which the following is a description.

My invention belongs to that general class of devices known as stanchions, and relates particularly to an improved stanchion, supporting means therefor, and means for simultaneously operating any desired number of stanchions of a series. The invention has among its objects the production of a device of the kind described that is simple, convenient, easy and positive in operation, durable, efficient, ornamental and satisfactory for use wherever found applicable. More particularly it has among its objects the production of an improved stanchion construction, preferably double acting, which stanchions may be singly or simultaneously operated, and in which any one or more of the same may be locked shut and not be affected by the operation of any others. It also has as an object the production of a construction of the kind described in which the stanchions may be adjusted for various sizes of stock. Many other objects and advantages of my invention will be obvious to those skilled in the art from the disclosure herein made.

To this end my invention consists in the novel construction, arrangement and combination of parts herein shown and described, and more particularly pointed out in the claims.

In the drawings, wherein like reference characters indicate like or corresponding parts,

Figure 1 is a view in elevation from the rear of several assembled stanchions and co-operating parts;

Fig. 2 is an enlarged view of the upper end of one of the stanchions, shown in Fig. 1, a part removed to show the construction;

Fig. 3 is a top plan view of the same with said part in place;

Fig. 4 is a sectional view taken substantially on line 4-4 of Fig. 2;

Fig. 5 is a sectional view taken substantially on line 5-5 of Fig. 2, and

Fig. 6 is a sectional view taken substantially on line 6-6 of Fig. 2.

Referring to the drawings, in which the

preferred embodiment of the invention is shown, I have illustrated a plurality of double acting stanchions. Each stanchion shown consists of the parts 1 and 2 suitably anchored at their lower ends and supported at their upper ends. The lower ends may be anchored in any desired manner. As shown they are pivotally and adjustably secured at 3 to a bar 4, provided with a stud or pin 5 pivotally secured to a bar 7 supported by the frame part 6-6. It is unnecessary to further describe the anchoring and construction of the lower end of the stanchion in detail, as the bar 7 forms a part of a separate application. The frames 6-6 are preferably constructed as shown, or in an equivalent manner, and secured to the floor or curb in any desired manner. As shown, the two parts or legs 6-6 are connected by a preferably curved head consisting of a part or the similarly formed parts 8-8, or their equivalents, which may be secured in place by the bolts or screws 9, or equivalent means for the purpose. The head parts 8 are formed so as to provide a slot 10 at the lower end and upper sides thereof. The stanchion parts 1 and 2 are formed with the ends 11 and 12, which are provided with the adjustable parts 13 and 14 and the parts 16 and 16' respectively, the same having the projecting ends 21 and 21' arranged as shown. Part 16 is formed with the gear rack or toothed part 17 and part 16' with a similar rack 17', the two racks being spaced, as most clearly shown in Figs. 5 and 6. They are also slightly curved as shown in the preferred construction. Arranged between the racks and carried by the head is a shaft 20, upon which is mounted a pinion or gear 19 arranged to mesh with the racks 17 and 17'. Obviously, if one stanchion part is moved it moves the rack connected therewith, and this, through the pinion 19, moves the other rack in the opposite direction, causing the stanchion parts to approach each other or separate, as the case may be. As shown in Fig. 1, the head is slotted as at 17" (on both sides) and a screw or the equivalent passed through and into the rack. These serve as guides for the free end of the racks and prevent the same from binding.

To simultaneously operate a series of stanchions, I provide an operating bar 22. The bar 22 is slidably carried by the bracket 23, or its equivalent, supported in any desired manner. One of the projecting parts 21 or

21', as shown 21', is provided with a latch member 24, pivotally carried thereby, the same being formed with notches 24' on the opposite sides (see Figs. 1 and 2). The latch 5 24 is so pivoted to the extension 21' that it may be swung from one side to the other thereof. The object of having these two notches will be more fully explained hereafter. The bar 22 carries a bracket 25 10 mounted on the rod. The bracket 25 is made adjustable on the rod so that it may be positioned at the desired point to operate the stanchions in the desired manner, as herein-after described. The construction may be 15 as is most clearly shown in detail in Fig. 6, in which latch 24 is arranged to detachably engage the bolt 26 on bracket 25, which bolt also serves to lock the bracket on the rod 22. Any equivalent construction may, of course, 20 be employed. In this case bolt 26 is formed with the head 28 and provided with a spacer 27, or the equivalent, upon which the latch 24 engages the nut 29, locking the parts together. A spring 30, or its equivalent, may 25 be mounted on the bar 22 between the brackets 23 and 25, the same tending to normally maintain the stanchions open or throw them to open position, as shown in Figs. 1 and 3. Any number of springs may be employed 30 upon the bar 22, one for each stanchion being shown. However, ordinarily it is not necessary to use any, and at least not to place one on the bar for each stanchion as shown. As described, the spring maintains the bar 35 or tends to throw it for open positions of the stanchions, means being provided for throwing the same to locking position against the action of the spring and maintain it in locked position. 40 For throwing the stanchions to closed position, I provide a lever or arm 35, which is connected by link 31, or the equivalent, to the bar. In the construction shown the link is pivotally secured at 33, to the arm 35 and 45 at 32 to the bar. The arm 35 is pivotally supported at 34 to the bracket 36 on the stanchion head. Obviously, an equivalent construction might be employed for the purpose. 50 As most clearly shown in Figs. 3 and 4, it will be noted that I have provided the part 16 with 21, similar to the other part 21'—37 being a pin or bolt projecting therethrough. When the latch 24 is thrown over to the dotted 55 position indicated on the left hand stanchion in Fig. 1, the same is arranged to engage with the part 21 or pin 37, and lock the two stanchion parts 1 and 2 together. On locking the two together, however, the latch is disengaged from the rod 22, so that 60 the stanchion or any other one in which the latch is so thrown, will for the time be disengaged from the controlling and actuating mechanism and be independent from any 65 other one. Any stanchion may in this man-

ner be disconnected from the bar 22, so that when the remaining stanchions are operated the stock retained by the unoperated stanchion will be locked in place. In this manner any one or more stanchions may be thrown 70 out of operation without affecting the operation of the others. It will also be noted by raising the latch 24, any stanchion may be independently operated without operating any of the others. Consequently any 75 one or more of the stock may be released without releasing the others.

Assuming the stanchions are open, as shown in Fig. 1, when the cattle are all in place, lever 35 may be operated to close the 80 stanchions, and it will be noted that if the lever is thrown, as shown in Fig. 3, the pivotal point or center 33 is below the center 34; consequently, any pull on the stanchions tending to open the same will be prevented until 85 the lever 35 is raised. However, any additional locking means may be employed, but when constructed as shown and described the same is ordinarily not necessary. Raising the lever 35 moves the bar 22, and through the 90 latches 24 positively pulls the stanchion parts open, movement of one part through the racks and gears throwing the other part to open position. In case of a single acting stanchion, of course only the movable side 95 would open.

To adjust the stanchion for different sized cattle it is only necessary to adjust the parts 13 and 14 on the stanchion parts 1 and 2. The stanchion may be constructed so that 100 the bottom may be adjusted by providing the additional holes in the parts 4, through which the pins 3 may pass. It will be noted that with this construction a separate stanchion head is not necessary, as the parts 6 and 8 not only form the stall head frame but provide a stanchion support to which the stanchions are directly connected. In setting up the stall frame the partitions 39, and connecting members shown, or their 110 equivalents, are ordinarily provided.

It may be mentioned that in the drawings I have not considered it necessary to endeavor to illustrate the parts in their proper relative proportions, as changes in the proportions of the parts would in no wise affect the operation. 115

Having thus described my invention, it is obvious that various immaterial modifications may be made in the same without departing from the spirit of my invention; hence I do not wish to be understood as limiting myself to the exact construction, arrangement or combination of parts herein shown and described, or uses mentioned. 120

What I claim as new and desire to secure by Letters Patent is:—

1. In a device of the kind described and in combination, a stall frame comprising a tubular cross-part having supporting legs 130

therefor, said cross-part slotted for a portion of its length, stanchion members having their lower ends suitably anchored and their upper ends extended to adjacent said cross-part, said stanchion members each provided with an adjustable part having an extension pivoted thereto and projecting through the slot in said cross-part, each projecting part having a gear rack thereon and a gear arranged in said cross-part between said racks.

2. In a device of the kind described and in combination, a stall frame comprising a cross-part having depending legs therefor, said cross-part slotted for a portion of its length, stanchion members having their lower ends suitably anchored, said stanchion members each provided with an end part pivoted thereto and projecting through the slot in said cross-part, each projecting part having a gear rack thereon, and a gear arranged in said cross-part between said racks, means for controlling the operation of said racks, comprising an operating bar, a latch carried by one projecting member and arranged to engage with said bar.

3. In a device of the kind described and in combination, a stall frame comprising a cross-part having two depending legs therefor, said cross-part slotted for a portion of its length, stanchion members having their lower ends suitably anchored, said stanchion members each provided with a part pivoted thereto at its upper end and projecting through the slot in said cross-part, each projecting part having a gear rack thereon, and a gear arranged in said cross-part between said racks, means for controlling the operation of said racks, comprising an operating bar, a latch carried by one of said projecting parts and arranged to detachably connect the same with said bar, and means for automatically moving said bar to open the stanchion.

4. In a device of the kind described and in combination, a stall frame comprising a cross-part having depending legs therefor, said cross-part slotted for a portion of its length, stanchion members having their lower ends suitably anchored, said stanchion members each provided with an adjustable part having an extended part pivotally secured thereto and projecting through the slot in said cross-part, each projecting part having a gear rack thereon, and a gear arranged in said cross-part between said racks, means for controlling the operation of said stanchions, comprising an operating bar, a latch arranged to engage with said bar and carried by one of said projecting members, and means for positively moving the bar to maintain the stanchion in closed positions.

5. In a device of the kind described and in combination, a stall frame comprising a curved cross-part having depending legs therefor, said cross-part slotted for a portion of its length, stanchion members having

their lower ends suitably anchored, said stanchion members provided with a part projecting through the slot in said cross-part, each projecting part having a curved gear rack thereon, and a gear arranged in said cross-part between said racks, means for controlling the operation of said stanchions, comprising an operating bar, a latch carried by one member connecting with said bar and arranged to engage with the other one of said projecting members, means for automatically moving said bar to release the stanchion, and means for positively moving the bar to maintain the stanchion in closed positions.

6. In a device of the kind described and in combination, a plurality of stall frames, each having a substantially horizontally extending tubular head part and supporting legs therefor, a stanchion for each stall frame having the upper ends thereof adjacent the stall frame head part, laterally adjustable means on each stanchion part, provided with means pivotally secured thereto for connecting the upper ends of said stanchions with said head part, said pivoted means projecting into the stall frame head part, means arranged in each stall head part for controlling said stanchions, and means carried adjacent said head part and operatively connected with said controlling means for actuating said controlling means.

7. In a device of the kind described and in combination, a stall frame comprising a tubular cross-bar having two depending legs therefor, said cross-bar slotted on opposite sides for a portion of its length, coöperating stanchion members, adjustable means for anchoring the lower ends of said stanchion members, said stanchion members each provided with an adjustable part at its upper end having a part pivotally secured thereto and projecting through the slots in said cross-bar, means in said cross-bar of said stall frame for connecting said parts, whereby movement of one will be transmitted to the other, and means carried by one part for engaging the other and preventing relative movement of the two.

8. In a device of the kind described and in combination, a stall frame comprising a cross-bar having two depending legs therefor and slotted at its under and upper sides for a portion of its length, stanchion members having their lower ends adjustably and pivotally anchored, said members provided with adjustable parts at their upper ends projecting through the slots in said cross-part, means arranged in said cross-part for operatively connecting said projecting parts, means for controlling the operation of said stanchions comprising an operating bar extending adjacent the stall frame cross-bar, a latch carried by one stanchion part, said latch arranged with notches therein and movable

- to engage with said bar or the other stanchion part, whereby the stanchion part may be disconnected from said bar, and locked to the other part as desired.
5. 9. In a device of the kind described and in combination, a stall frame comprising a cross-bar having two depending legs therefor and slotted at its under and upper sides for a portion of its length, stanchion members having their lower ends adjustably and pivotally anchored, said members provided with adjustable parts at their upper ends projecting through the slots in said cross-
10 parts, means arranged in said cross-part for operatively connecting said projecting parts, including a rack carried by each part, a pinion arranged between said racks, and means for guiding the racks, means
15 for controlling the operation of said stanchions comprising an operating bar extending adjacent the stall frame cross-bar, a latch carried by one stanchion part, said latch arranged with notches therein and movable to engage with said bar or the other stanchion part, whereby the stanchion part may be disconnected from said bar, and locked to the other part as desired, and means for positively actuating said bar.

In testimony whereof, I have hereunto signed my name in the presence of two 30 subscribing witnesses.

CHARLES M. STEVENSON.
